ATTORNEY

UNITED STATES PATENT OFFICE.

OSKAR ALBERT SCHULTZ, OF ELLERBECK, GERMANY.

RATCHET-DRILL.

SPECIFICATION forming part of Letters Patent No. 712,856, dated November 4, 1902.

Application filed January 2, 1902. Serial No. 88,143. (No model)

To all whom it may concern:

Be it known that I, OSKAR ALBERT SCHULTZ, a subject of the Emperor of Germany, residing at Ellerbeck, Germany, (whose 5 post-office address is 23 Trenenallee, Ellerbeck-Kiel,) have invented certain new and useful Improvements in Ratchet-Drills; and I do hereby declare the following to be a full, clear, and exact description of the invention, 10 such as will enable others skilled in the art to which it appertains to make and use the same, reference being had to the accompanying drawings, and to letters of reference marked thereon, which form part of this 15 specification.

The present invention has reference to improvements in ratchet-drills, and relates more especially to an adjustable feed spindle or shaft for ratchet-drills; and the object of the 20 invention is to provide a feed-spindle which can be lengthened so as to accommodate the drilling-tool to the varying distances from the counter-rest to the work-piece without the use of interposed loose parts, as pieces of 25 wood or metal, as are used now in places where the boring depth or the distance from the counter-rest to the work-piece is comparatively great—for instance, in boilers and the like.

According to the present invention the feed-spindle is composed of several parts or sections telescoping into one another, which according to necessity are drawn out one by one and rigidly secured in the drawn-out position.

In order to make the invention more readily understood, I have illustrated it on the accompanying sheet of drawings, in which—

Figure 1 represents a longitudinal section 40 through a feed-spindle composed of three telescoping sections. Fig. 2 is a side view of the device turned at an angle of ninety degrees with respect to Fig. 1. Fig. 3 is a cross-section on line *a b* of Fig. 1, and Fig. 4 shows 45 the mode of connection with a ratchet-drill.

In the drawings only three telescoping sections are shown, but it is evident that four or more such sections may be provided. The section B receives the solid extension-piece 50 C. The section A is provided with the center point D. Upon the outer surface of the section A are secured two or more leaf-springs

O, with enlarged upper ends G in the form of wedges and having inclined or beveled outer faces with noses L, adapted to project into 55 and through corresponding slots H, provided in the wall, as is clearly shown in the upper part of Fig. 1. The upper end of the section B is provided with an exterior thread M, upon which threads a nut E, having a cone-shaped 60 annular extension N, the inner surface of which has the same degree of slant as the enlarged leaf-spring ends. Upon the nut E being screwed down the noses L are pressed through the slots H and into corresponding 65 recesses H', provided in the solid extension-piece C, thereby rigidly securing the latter within the section B. The same arrangement of springs, recesses, slots, and cone-nuts is found with reference to sections A and 70 B and the other sections, however many of them may be used.

The extension-piece C carries a socket-piece J with internal thread for receiving the intermediate member K, which in turn surrounds the feed-screw L'. The slots H H' may be provided at varying distances or equal distances and may be marked so that the workman is enabled to directly read off the depth of the bore-hole.

In the operation of the invention the drill may be adapted to bore holes in boilers of different sizes or in other situations where the bearing of the center point D is too far from the point of operation of the drill-point by 85 connecting up one or more telescoping sections in the manner described, adjustments in shorter distances than whole sections being made by adjusting the noses L of springs O in different slots H H' of one or more of the 90 inner sections.

The described extension shaft or spindle can easily be fitted to the ordinary ratchet-drill by providing the ordinary center-point spindle with an exterior thread adapted to 95 engage the corresponding interior thread of the headpiece or socket J.

Having thus fully described my invention, what I claim as new, and desire to secure by Letters Patent of the United States, is—

An extensible feed shaft or spindle for ratchet-drills, comprising a plurality of telescoping sections, provided respectively with slots and corresponding recesses, the upper

section adapted to receive the feed-screw and the lower one carrying the center point, leaf-springs secured upon the slotted section and having enlarged upper ends and noses adapted to pass through the slots in one section and engage in the recesses in the other section, and a nut with a cone-shaped annular extension threaded upon the upper end of the slotted section and adapted to actuate and

hold the upper ends of the said leaf-springs in 10 the slots and recesses, substantially as and for the purposes specified.

In witness whereof I have hereunto set my hand in presence of two witnesses.

OSKAR ALBERT SCHULTZ.
